CREMATORIAL URN

August Klinzing, Milwaukee, Wis.

Application August 3, 1940, Serial No. 350,244

1 Claim. (Cl. 220—39)

My present invention relates generally to improvements in the art of manufacturing metallic containers, and relates more specifically to improvements in the construction of crematory urns and closures therefor.

Generally defined, an object of my invention is to provide an improved crematory urn which is simple and durable in construction, which may be readily manufactured, and which may be effectively sealed from the ambient atmosphere.

For many years, large numbers of persons have preferred to have their bodies cremated after their demise with the remains to be preserved in containers, commonly referred to as urns, manufactured especially for such purpose. In some instances, the urns are buried in cemetery lots or cemented in headstones after the remains have been placed therein. However, in many cases these crematory urns are placed in vaults or open and accessible spaces in cemetery chapels or the like and are in some instances even placed on fireplace mantels or other places of display in homes; and oftentimes it is customary to provide that the remains of more than one person be placed in the same urn, especially where there is a close relationship such as husband and wife. It is therefore highly desirable and in fact necessary for sanitary reasons to provide a crematory urn which may be hermetically sealed, which may be reopened to receive additional ashes, and which may moreover be ornamentally molded or designed for display purposes. It is furthermore essential that these urns be manufactured of some sort of metal or similar non-perishable material without the use of gaskets or the like to prevent deterioration thereof.

It is therefore a more specific object of the present invention to provide an improved crematory urn having a readily removable self-locking hermetic seal without necessitating the use of gaskets or the like and which may be manufactured of any suitable material at moderate cost.

Another specific object of the invention is to provide a simple air-tight seal for crematory urns which may nevertheless be easily removed for insertion of additional ashes without undesirable wear and replacement of parts and without reducing the effectiveness of the seal.

Still another specific object of my invention is to provide a crematory urn with a closure cap which is adapted to snugly conform to the surface immediately adjacent the mouth of the urn,

thereby reducing the necessity of careful machining.

A further specific object of my present invention is to provide a crematory urn having an effective sealing cap at the bottom thereof which aids in maintaining the balance without detracting from the appearance of the urn.

An additional specific object of the invention is to provide an improved crematory urn having an ornamental top portion and a hermetically sealed reinforced base portion adapted to set firmly on any relatively flat surface.

These and other objects and advantages will be apparent from the following detailed description.

A clear conception of an embodiment of the invention, and of the mode of constructing crematory urns in accordance with the improvement may be had by referring to the drawing accompanying and forming a part of this specification wherein like reference characters designate the same or similar parts in the several views.

Fig. 1 is a side elevation of one of my improved crematory urns, a portion being broken away to show the closure seal in cross-section;

Fig. 2 is a bottom view of the urn, a portion of the sealing cap being broken away to show the final seating;

Fig. 3 is an enlarged somewhat distorted transverse vertical section through a fragment of the urn and the sealing cap and showing the cap only partially applied;

Fig. 4 is a similarly enlarged and distorted transverse vertical section through a fragment of the urn and cap showing the cap in final sealing position; and

Fig. 5 is a transverse vertical section through the base portion and cap of a modified type of urn.

While the improved urn has been shown specifically as a crematory urn having a removable hermetic seal in the bottom portion thereof manipulable by means of a spanner wrench, it is not the intent to thereby unnecessarily restrict the scope, since the seal could obviously be placed elsewhere and other suitable tightening and removing tools may be utilized.

Referring to the drawing, the improved crematory urn comprises in general an ornamental container 8 having an integral outwardly flanged base portion 9 formed with a depending annular peripheral bead 10 surrounding a recess 11 which is provided with a more or less inwardly and upwardly tapered and machined surface 12 terminating at a threaded bore or mouth 13 located

- centrally of the base and extending into the interior of the container; and a closure cap 14 formed with screw threads 15, an annular cut-out portion 16, and an outwardly extending flanged head 17 formed with a relatively sharp inner peripheral edge 18 and having one or more holes 19 for receiving the pins of a spanner wrench.

In the manufacture of the improved assemblage, it has proven more desirable to utilize the same or similar metals for both the urn 8 and the closure cap 14, thereby reducing the bite of the edge 18 into the tapered surface 12 as the cap is screwed tightly into the threads of the opening 13 and consequently reducing wear due to repeated opening and closing of the urn. However, a tight seal also results if the urn is made of relatively soft material and the closure cap of a harder substance; and it is to be noted that the annular finished or machined surface 12 with which the flange 17 coacts, may be either flat, slightly tapered, or more abruptly tapered.

The sharp biting edge 18 may be formed in any manner, as by undercutting the adjacent side wall of the recess 16, so that when the cover is driven home the sealing edge will move directly toward the machined surface 12. It is to be noted, that tight sealing is effected without the use of gaskets, since the metal flange 17 and edge 18 of the cap 14 directly engages the annular finished surface 12.

Referring specifically to Fig. 3 it will be noted that a relatively loose fit is provided between the screw threads 13 of the urn and the threads 15 of the cap. This is important since it not only permits the flanged head 17 to conform to possible irregularities on the tapered surface 12 as the cap is screwed into sealing position, but also prevents the threads 13, 15 from locking or jamming before the sharp edge 18 is forced into intimate contact with or embedded in the metallic tapered surface 12 to finally seal the urn, as clearly shown in Fig. 4. In Figs. 3 and 4 the loose fit of the threads and the bite have been somewhat exaggerated in order to enhance the clearness of disclosure.

In the modification shown in Fig. 5, a portion of the base of a somewhat wider urn is disclosed, and the taper of the surface 12 has been considerably decreased. To insure a more rigid construction at the base portion of a wider urn wherein the base may be weakened by a thinner wall, outwardly or radially extending reinforcing ribs 20 are provided. These ribs may be readily formed integral with the base portion 11 without interfering with proper coaction between the peripheral bead 10 and supporting structure, and similar interchangeable caps may therefore be provided for urns of various sizes and proportions. In this modified form, the surface 12 is relatively flat, and the flange 17 again coacts directly with this finished surface 12.

It will be noted that after the ashes of the cremated person are inserted into the urn through the mouth thereof, the closure cap may be screwed into the mouth to close the urn. As the cap is being driven into place, the flange 17 and sharp edge 18 will directly engage the tapered

surface 12 and the loose fit provided in the threads will permit the edge 18 to tilt slightly at its periphery in any direction, thereby compensating for any possible irregularities on the surface 12. As more pressure is placed on the threads in the process of tightening the cap, the lower surface of the cap threads 15 will be forced downwardly against the upper surface of mouth threads 13, permitting air in the urn which is being displaced by the cap to escape, and also providing contact surfaces for forcing the sharp edge 18 directly into snug engagement with or into the metallic tapered surface 12. As this edge is forced more or less into the surface 12, a very effective air-tight seal is produced through which no powdery ashes and no gases can escape. The cut-out portion 16 provided between the threads 15 and the flanged head 17, insures escape of displaced air prior to the sealing, and provides sufficient clearance between the threads 13 of the urn and the flange 17 of the cap, when the urn is reopened and reclosed and the groove is cut deeper by the edge 18.

From the foregoing detailed description it will be apparent that my present invention provides an improved crematory urn assemblage which may be readily opened and closed for receiving ashes of several persons without impairing the effectiveness of the seal. The various portions of the urn and the cap are on the exterior and may consequently be readily machined, and the urn may be of any size, shape, or design without necessitating the use of gaskets, washers, or the like, and the machined surface may be either flat or more or less tapered. While I have shown a closure cap formed for manipulation with a spanner wrench, various other types of tightening and loosening tools could obviously be used without departing from the scope of the invention, but the provision of manipulating holes 19 directly within the cap 14 is desirable because it avoids external projections on the cap which might interfere with the stability of the base structure.

It should be understood that it is not desired to limit this invention to the exact details of construction or to the precise mode of use, herein shown and described, since various modifications within the scope of the claim may occur to persons skilled in the art.

I claim:

In a crematory urn, a receptacle having a circular access opening provided with internal V-shaped screw threads and also having a tapered annular machined surface adjoining the outer end of said opening and inclined symmetrically inwardly relative to the central opening axis, and a closure cap for said opening having external V-shaped screw threads loosely cooperable with said internal threads and also having an integral peripheral right angle flange extending outwardly over said machined tapered surface and provided with an annular machined relatively sharp biting edge portion on its peripheral edge adjacent the tapered surface adapted to be driven into direct sealing engagement with said tapered surface in a plane perpendicular to said axis by virtue of the taper of the loosely coacting V-threads.

AUGUST KLINZING.
